(57) **CLAIM**

The ornamental design for an oilfield blending unit, as shown and described.

DESCRIPTION

FIG. 1 is a top left perspective view of an oilfield blending unit that embodies the ornamental design;

FIG. 2 is a front elevation view of the oilfield blending unit;

FIG. 3 is a rear elevation view of the oilfield blending unit;

FIG. 4 is a left side elevation view of the oilfield blending unit;

FIG. 5 is a right side elevation view of the oilfield blending unit;

FIG. 6 is a top plan view of the oilfield blending unit; and,

FIG. 7 is a bottom plan view of the oilfield blending unit. The broken lines show portions of an oilfield blending unit which form no part of the claimed design.

1 Claim, 6 Drawing Sheets(56)
